US00D842882S

(12) **United States Design Patent** (10) **Patent No.:** **US D842,882 S**
Bachman et al. (45) **Date of Patent:** **** Mar. 12, 2019**

(54) **DISPLAY SCREEN OR PORTION THEREOF
WITH GRAPHICAL USER INTERFACE**

(71) Applicant: **Apple Inc.**, Cupertino, CA (US)

(72) Inventors: **William Martin Bachman**, San Jose, CA (US); **Colin Bennett**, San Francisco, CA (US); **Graham Clarke**, Mountain View, CA (US); **Jennifer Lynn Carley Folsé**, San Francisco, CA (US); **Monika E. Gromek**, Oakland, CA (US); **Alexander W. Johnston**, San Francisco, CA (US); **Dennis Park**, San Francisco, CA (US); **Brian K. Shiraishi**, Belmont, CA (US); **Jeff Tan-Ang**, San Jose, CA (US); **Christopher Wilson**, San Francisco, CA (US)

(73) Assignee: **Apple Inc.**, Cupertino, CA (US)

(**) Term: **15 Years**

(21) Appl. No.: **29/617,046**

(22) Filed: **Sep. 11, 2017**

(51) LOC (11) Cl. **14-04**

(52) U.S. Cl.

USPC **D14/486**

(58) **Field of Classification Search**

USPC **D14/485, 486; D20/11**

CPC G06F 3/048; G06F 3/0481; G06F 3/04812; G06F 3/04815; G06F 3/0482; G06F 3/0487

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The peripheral dashed broken lines illustrate a display screen or portion thereof, and form no part of the claimed design. The portions of the graphical user interface shown in grayscale form no part of the claimed design.

1 Claim, 1 Drawing Sheet
